FRUIT BOX OR THE LIKE

Gilbert Lucien Herman, Domaine de Castang,
G.F.A. 24, Bergerac, France

Filed Dec. 27, 1972, Ser. No. 319,040

Claims priority, application France July 19, 1972

Term of patent 14 years

Int. Cl. D9—03

U.S. Cl. D9—243

FIG. 1

FIG. 2

FIG. 3

2L

FIG.6

FIG. 7

FIG. 8

FIG. 1 is a top, front perspective view of a fruit box or the like showing my new design;

FIG. 2 is a cross-sectional view taken on the line 2—2 of FIGS. 1 and 3;

FIG. 3 is a front elevational view;

FIG. 4 is a bottom plan view;

FIG. 5 is a top plan view;

FIG. 6 is a rear elevational view;

FIG. 7 is an end elevational view looking from the left of FIG. 3; and

FIG. 8 is an end elevational view looking from the right of FIG. 3.

I claim:

The ornamental design for a fruit box or the like, as shown and described.
